LEWIS C. MYERS, OF BROOKLYN, NEW YORK, ASSIGNOR, BY MESNE ASSIGNMENTS, TO ROYAL TYPEWRITER COMPANY, INC., OF NEW YORK, N. Y., A CORPORATION OF NEW YORK.

RIBBON MECHANISM FOR TYPE-WRITING MACHINES.

1,088,790.

Specification of Letters Patent.

Patented Mar. 3, 1914.

Application filed June 13, 1912. Serial No. 703,383.

To all whom it may concern:

Be it known that I, LEWIS C. MYERS, a citizen of the United States of America, residing in the borough of Brooklyn, county 5 of Kings, and State of New York, have invented a certain new and useful Improvement in Ribbon Mechanism for Type-Writing Machines, of which the following is a specification.

10 This invention relates to ribbon mechanism where the ribbon vibrator is capable of different ranges of movement to print either from an upper or lower zone of the ribbon and in which, to prevent overthrow of the 15 vibrator, positive limiting stops are provided to determine the extent of movement of the ribbon vibrator in either case. Furthermore, the organization is one in which the means of adjusting the throw of the 20 ribbon vibrator simultaneously adjusts the stop devices. The organization, except as hereinafter appears, is the same as that disclosed in U. S. patent to Edward B. Hess, No. 984,671, of February 21, 1911. The ribbon 25 actuating means are the same and this invention only differs from that patent in respect to the visible manually operated devices which the operator manipulates to determine the adjustments, and the means for 30 definitely positioning the parts and holding them in adjusted position.

The accompanying drawing shows so much of a Royal Standard typewriting machine, the general construction of which is 35 well understood, as is thought to be necessary to illustrate this invention.

Figure 1 is a right hand elevation of the essential parts detached from the frame, showing in dotted lines the parts in position 40 for upper case printing; Fig. 2, a detailed elevation of some of the parts shown in Fig. 1; Fig. 3, a bottom plan view of the escapement frame and associated parts that are relevant to this invention; and Fig. 4, a detailed plan view showing the hand manipulated parts by which the operator effects 45 adjustments, and Fig. 5 a detailed view showing the contour of the stop device.

The ribbon vibrator bell crank of which 1 50 is the forwardly extending arm and 2 the downwardly extending arm, is pivoted at 3 in a bracket 4 depending from the escapement frame 5. Its front end is to be pinned to the ribbon vibrator 5^x and a coiled reac-

tion spring is to be applied to a projection 55 thereof, 3', extending rearwardly beyond the pivot 3. A horizontally disposed lever 6 is pivoted intermediate its ends at 7 in the end of the bell crank arm 2. The rear end of the lever 6 is enlarged or widened vertically and 60 its edge is formed with surfaces 8, 9 in different planes either one of which surfaces, according to the adjustment of the lever 6, coöperate with means actuated when printing operations occur to urge the lever 6 forward and so determine the throw of the ribbon operating bell crank to effect printing from either an upper or lower zone of a ribbon. Thus the drawing shows a swinging frame 6^x carrying the universal bar 7^x that 70 acts upon the surfaces 8, 9. This is all as shown in the Hess patent above mentioned. A link 10 connects the forward end of lever 6 with a rotatable crank stop block 11 fast on a shaft 12 that extends from the right 75 hand side of the machine and has bearings in the escapement frame 5. The rotatable crank stop block 11 is formed with a hub 13 and provided with a set screw for attaching it to the shaft and is located approximately 80 in the center of the machine. This cam block has surfaces of different radius. One surface 11' is of greater radius than the other 11². If lever 6 is set to impart the maximum movement to arm 1 of the bell 85 crank lever upward movement of the latter will be positively limited by stop surface 11²: whereas if as in Fig. 1, the surface 9 of lever 6 is in operative position a less upward movement will be imparted to the bell crank 90 arm 1 in which case it will be, as shown, arrested by stop surface 11'. Adjustments of the stop surfaces and of lever 6 are made as follows: On the shaft 12, to the right of the escapement frame, is secured a toothed 95 wheel 14 having three recesses formed by two stops 15-16 and two teeth 17, 18. The recesses are V shaped but are relatively wide; that is to say, the walls forming the recesses have considerable pitch. On the 100 right hand side of the escapement frame is a downwardly inclined arm 19 pivoted to the frame at 20. In its lower end is a short stud shaft carrying a roller 21 that coöperates with the wheel 14 and into engagement with 105 which it is drawn by a coiled spring 22 one end of which is attached to arm 19 and the other to a projection 23 on the side of the

escapement frame. On the shaft 12 toward the right hand side of the machine is secured an upright arm 24 to which is connected a forwardly extending operating link 25.

6 The operation will be plain. The roller 21 pressed by the positively acting strong spring 22 into recesses of wheel 14 serves to determine exactly the adjustment of lever 6 and stop surfaces 11', 11''. Thus, as seen in Fig. 1, the adjustment is for printing from the upper zone of the ribbon and the roller 21 seats in the center angular recess of the wheel 14 holding all the parts firmly in adjusted position. If link 25 is thrust rearwardly, wheel 14 will revolve and roller 21 will be transferred to the bottom of the next recess in which position surface 8 of the lever 6 will be maintained in operative 10 position the forward end of the lever having been lifted by link 10. The stop 15 of wheel 14 prevents overthrow in that direction. If, however, link 25 be drawn forward, roller 21 will be transferred to the 15 other side recess in which position the end surfaces 8, 9, of lever 6 will be lifted clear of the device that operates thereon so that there will be no movement of the ribbon vibrator which will then be held in its lowest 20 position, when stencil work may be done. The stop 16 operates to prevent overthrow in this latter adjustment.

30 Experience has demonstrated that a wheel such as 14 coöperating with a strong substantial arm and roller such as 19 and 21 controlled by a coiled spring of appropriate strength and tension affords very positive results and is never liable to become disarranged, or any of its parts worn or broken, 35 or become so worn as to affect the accuracy of all its adjustments.

40 The means by which the operator may actuate the draw and thrust rod 25 is as follows: At the right hand side of the machine is a vertical shaft 26 having a lower bearing 27 in a bracket 28 extending from the side of the main frame of the machine. On this shaft is secured a laterally projecting radial arm 29 of which 30 is the hub 45 secured to the shaft by set screw. The upper end of the shaft passes through the dust guard or right hand cover plate of the machine and has secured to its upper end a crank arm 32 having a vertical manipulating handle or knob 33. On the forward edge 50 of this crank arm is a projecting pointer 34 and inscribed upon the face of the dust guard (or side cover plate of the machine) suitably spaced are the words "Stencil", 55 "Top", "Bottom". It will be seen that when the arm 32 is in central position as shown by the full lines the parts are in the position indicated in Fig. 1 for printing from the upper zone of the ribbon in which 60 printing position is indicated by the relation

65 of the pointer to the word "Top". When the adjusting crank arm is thrown to the lowermost position as indicated by the dotted lines the pointer 32 is at the word "Bottom" in which position the ribbon mechanism will be adjusted so that the surface 8 of the lever 6 is in operative position and printing may be effected from the bottom zone or band of the ribbon; and, when the arm 32 is thrown rearwardly to the position indicated by the dotted lines in Fig. 4, the 70 parts will be adjusted for stencil work.

75 The construction described has the merit of being very inexpensive, substantial, positive and accurate in all its adjustments and actions; the means of adjustment are in plain sight and convenient reach of the operator who can always see the position in which the ribbon operating devices are set.

I claim:

1. Ribbon mechanism for a typewriting machine, comprising a ribbon vibrator, adjustable means for throwing the vibrator through different distances to effect printing from an upper or a lower zone of a ribbon, adjustable stop devices for limiting the throw of the vibrator when printing from either zone, means for simultaneously adjusting the vibrator actuating means and the stop devices and means for accurately positioning and holding the stop devices and vibrator actuating means, said holding means comprising a recessed wheel, a pivoted arm having a projection engaging the recesses in the wheel and a coiled reaction spring applied to said arm.

2. Ribbon mechanism for a typewriting machine, comprising a ribbon vibrator, adjustable means for throwing the vibrator through different distances to effect printing from an upper or a lower zone of a ribbon, adjustable stop devices for limiting the throw of the vibrator when printing from either zone, means for simultaneously adjusting the vibrator actuating means and the stop devices and means for accurately positioning and holding the stop devices and vibrator actuating means, said holding means comprising a recessed wheel, a pivoted arm having a projecting roller engaging the recesses in the wheel and a coiled reaction spring applied to said arm.

3. Ribbon mechanism for a typewriting machine, comprising a ribbon vibrator, adjustable means for throwing the vibrator through different distances to effect printing from an upper or a lower zone of a ribbon, adjustable stop devices for limiting the throw of the vibrator when printing from either zone, means for simultaneously adjusting the vibrator actuating means and the stop devices and means for accurately positioning and holding the stop devices and vibrator actuating means, said holding means comprising a wheel having limiting

- stops 15, 16 and intermediate teeth forming recesses, a pivoted arm having a lateral projection engaging said recesses and a coiled reaction spring applied to the arm.
6. Ribbon mechanism for a typewriting machine, comprising a ribbon vibrator, adjustable means for throwing the vibrator through different distances to effect printing from an upper or a lower zone of a ribbon, 10 adjustable stop devices for limiting the throw of the vibrator when printing from either zone, means for simultaneously adjusting the vibrator actuating means and the stop devices and means for accurately 15 positioning and holding the stop devices and vibrator actuating means, said holding means comprising a movable part having positioning faces, an arm coöperating therewith and a coiled reaction spring applied 20 to the arm.
5. Ribbon mechanism for a typewriting

machine, comprising a ribbon vibrator, adjustable means for throwing the vibrator through different distances to effect printing from an upper or a lower zone of a ribbon, 25 adjustable stop devices for limiting the throw of the vibrator when printing from either zone, means for simultaneously adjusting the vibrator actuating means and the stop devices and means for accurately 30 positioning and holding the stop devices and vibrator actuating means, said holding means comprising a rotatable part having positioning faces an arm coöperating therewith pivoted upon the frame and a coiled 35 reaction spring applied to the arm.

In testimony whereof, I have hereunto subscribed my name.
